DESIGN FOR AN ELECTRIC SWITCH CABINET HANDLE

William C. Anderson, Bromley, Ky., and Frank
Harvey, Cincinnati, Ohio

Application April 1, 1939, Serial No. 83,993

Term of patent 14 years

To all whom it may concern:

Be it known that we, William C. Anderson and Frank Harvey, citizens of the United States, residing at Bromley, county of Kenton, State of Kentucky, and Cincinnati, county of Hamilton, State of Ohio, respectively, have invented a new, original, and ornamental Design for an Electric Switch Cabinet Handle, of which the following is a specification, reference being had to the accompanying drawing, forming part thereof.

Fig. 1 of the drawing is a front elevational view of an electric switch cabinet handle showing my

new design as it appears with the handle in inoperative position.

Fig. 2 is a side elevational view thereof, with the handle in operative position, the escutcheon plate being shown in section.

Fig. 3 is a front elevational view with the handle in operative position.

We claim:

The ornamental design for an electric switch cabinet handle, as shown and described.

WILLIAM C. ANDERSON.
FRANK HARVEY.
